UNITED STATES PATENT OFFICE.

WILLIAM LILE, OF VENICE, ILLINOIS.

TROLLEY-POLE-CONTROLLING DEVICE.

No. 855,732.

Specification of Letters Patent.

Patented July 2, 1907.

Application filed June 28, 1906. Serial No. 323,953.

To all whom it may concern:

Be it known that I, WILLIAM LILE, a citizen of the United States, residing at Venice, in the county of Madison, and State of Illinois, have invented certain new and useful Improvements in Trolley-Pole-Controlling Devices, of which the following is a full, clear, and exact description, reference being had to the accompanying drawings, forming a part hereof.

My invention has relation to improvements in trolley-pole controlling devices; and it consists in the novel construction of mechanism, more fully set forth in the specification and pointed out in the claims.

In the drawings, Figure 1 is a middle vertical section on line 1—1 of Fig. 4, showing the operating parts of the device in normal operation; Fig. 2 is a similar section showing the parts displaced upon the release of the pole from the trolley-wire; Fig. 3 is a horizontal section on line 3—3 of Fig. 1; Fig. 4 is a horizontal section on line 4—4 of Fig. 1; Fig. 5 is a vertical sectional detail enlarged, taken on the line 5—5 of Fig. 3; and Fig. 6 is a vertical section on line 6—6 of Fig. 5.

The object of my invention is to provide suitable mechanism which will permit the trolley-pole to drop away from the trolley-wire when the trolley jumps the wire, instead of permitting the pole to swing or fly upward under the tension of the spring which keeps it in contact with the wire under normal conditions.

In trolleys as now generally constructed, when the wheel leaves the wire, the tension of the controlling spring forces the pole to a substantially vertical position; and if the car happens to be in rapid motion, the pole will strike against the guy wires which support the trolley wire, the impact frequently resulting in considerable damage to the wires. With my present improvement the tension of the spring which holds the trolley to the wire is at once destroyed or rendered ineffective the moment the pole leaves the wire, thereby permitting the pole to drop toward the roof of the car, when it can subsequently be restored to its working position by the conductor from the inside of the car. In detail the invention may be described as follows:

Referring to the drawings, C represents a section of the car roof provided with glass panels or windows W, on either side of the center of the roof, the latter having rotatably mounted at such center a casing 1 carrying at its lower end a hand-wheel 2. The casing is provided with a flange 3 trough-shaped in cross-section, the base of the trough being provided with an insulating ring 4 carrying a conducting plate or ring 5 from which depend a series of brushes 6 operating in conjunction with a contact plate 7 supported on an insulating disk 8 which latter rests on the flanged portion of a suitable

supporting ring or bearing 9 secured to the car-roof. Leading to the plate 7 is a properly insulated section of the conducting wire w, the plate 5 having a similar wire w' leading to the trolley pole P. The pole is pivoted in a bracket 1' forming an extension of the casing 1, the base of the pole terminating in a pinion 10 disposed about the axis of oscillation of the pole, the pinion meshing with the teeth of a vertically reciprocating rack-bar 11 loosely operating through the closed top of the casing 1, and guided by the ribs 12 operating in corresponding grooves 13 formed in the sides of the bracket 1'. Mounted on a lateral projecting arm 14 of the bracket 1' is a sleeve or tube 15 over which is free to play a ring 16 or collar 16 from which extend the tension rods 17, the opposite ends of said rods connecting to the eye-bolts 18 mounted in the lateral brackets 19 at the base of the pole. The sleeve 15 is encompassed by an expansion spring 20 confined between the collar 16 and the bracket 1', the tension of the spring being regulated by the nuts 21 at the outer ends of the rods 17. The point of connection of the rods 17 with the pole P is above the axis of oscillation of the pole as shown in the drawings.

The lower portion of the rack-bar 11 terminates in a U-shaped bolt or fork 22 whose lower end is secured to a disk 23 confined in the casing 1, the fork 22 passing loosely through a second disk 24, the latter disk being secured to the end of a similar fork 25 which in turn passes loosely through the disk 23 (Fig. 3), the forks being disposed in planes at right angles to one another so as to readily telescope with one another. The base of the fork 25 carries a stem 26 operating loosely through the hand-wheel 2, the projecting end of the stem being pivotally coupled to an intermediate point of a vertically oscillating setting lever 27 pivoted at one end to a link 28 depending from the hand-wheel. Between the disks 23, 24, is interposed an expansion spring 29 for which under normal conditions of operation, the disk 24 serves as a stationary abutment, the disk 23 being the movable abutment and responding to the tension of the spring. It will be readily seen that if the disk 24 be anchored, or held stationary, the tension of the spring will drive the disk or movable abutment 23 before it, thereby drawing down on the fork 22 and rack-bar 11 and forcing the pole (by rotating the pinion 10) against the trolley-wire T. This condition accords with the normal operation of the parts; and the tension of the spring 29 is rendered ineffective only by the removal of the support for the stationary abutment 23, for then, the spring having no stationary support against which to brace itself ceases to drive the movable abutment 23 before it, and the parts being thus released from the action of the spring, the pole drops to the roof.

of the car (see dotted position of the parts in Fig. 2); and to prevent a too sudden drop when thus released, the pole is allowed to fall slowly under the restraining influence of the balancing spring 20 against which it must 5 act in its draft on the tension rods 17 and the movable collar or follower 16. The advantage of course in allowing the pole to drop is to avoid injury to the overhead system of wires as often happens in the case of poles jumping the trolley wire.

10 Should the pole jump the wire, the stationary abutment 24 would be instantly released from its anchored position and the pole would drop as described. I will now describe the mechanism for anchoring the abutment 24, and the manner in which the abutment is 15 released in the event the pole jumps the wire: Pivoted to the setting lever 27 at a point beyond its connection with the stem 26 is a serrated or ratchet arm 30 adapted to engage a corresponding serrated bearing plate 31 carried by the hand-wheel 2, the arm being capable of 20 retraction from said bearing by the spring 32. Mounted on the hand-wheel 2 and rotatable in a vertical plane is a trigger 33 to whose axis of rotation is secured a cam 34 which, when the trigger is rocked to the position shown in Fig. 1, forces the serrated arm 30 into engagement with its bearing plate 31, thereby not only locking the lever 27 against movement, but securely anchoring the disk 24 coupled to the lever through the connections 26, 25. The upper end of the trigger moreover carries a pivoted latch 35 whose terminal hook 36 25 (Fig. 6) through the medium of the spring 37 is forced into engagement with the upper end of a sliding bolt or keeper 38 mounted in a casing 39, the wall of the latter being provided with a peripheral slot 40 through which operates the laterally projecting arm 41 of the keeper.

30 The arm 41 terminates in a fork 42 loosely embracing a vertically reciprocating rod 43 between the lugs 44, 44 carried by said rod, the latter operating loosely through the hand-wheel 2 and through an eye-bolt 45 secured to the casing 1, and terminating at its lower 35 end in a lobe or button 46, and at its upper end in a head 47 between which and the eye-bolt 45 is confined an expansion spring 47'. The upper half of the rod 43 is screw-threaded, over which screw-threaded portion is passed a tappet arm 48 permitted to move vertically 40 by the walls of the vertical slot 49 in the casing 1, but prevented from rotating about said rod. By turning the latter (the operator seizing the lobe 46) in proper direction, the position of the tappet 48 along the rod can be accurately adjusted.

45 The parts in Fig. 1 are shown in locked position and the pole is on the wire. Should the pole jump the wire, the tension of the spring 29 will immediately force the abutment 23 downward (it being remembered that the abutment 24 is anchored) until it impinges against and depresses the tappet 48. This will depress the tappet-rod 43 and its lugs 44, 44 between which the forked end of the arm 41 of the keeper 38 is confined, thereby depressing the keeper and withdrawing it from the latch 35. This sudden withdrawal of the keeper from the 50 latch permits the tension of the spring 32 to assert itself, drawing the serrated arm 30 against the cam 34, the pressure against the latter being at a suitable point above the axis of rotation of the cam, and this action

coupled with the further fact that the lower arm of the trigger 33 is considerably weighted or heavier than the upper arm, serves to trip the trigger and cam away from the arm 30, allowing the spring 32 to retract the arm from its bearing plate 31 (Fig. 2) when the anchorage for the abutment 24 is destroyed, and the driving spring 29 having no stationary abutment or support 55 against which to brace itself, the device collapses as it were, the tension of the spring becomes ineffective and the pole drops as already described (Fig. 2). The conductor then by seizing the hand-wheel 2 can turn the casing so as to bring the end of the pole directly under the wire T, (a clear vision being afforded him through the window W) then by pulling down on the lever 27 he can reset the parts by forcing the locking arm 30 against its plate 31; and rocking the trigger 33 to cause the latch 35 thereof to reengage its keeper 38. 60 Of course under ordinary conditions the pole may oscillate more or less vertically (for variable elevations of the trolley wire) without effecting a release of the stationary abutment 24, since the arc of rotation of the pinion 10 for even a considerable oscillation of the pole would be relatively small, and hence the reciprocations imparted to the rack-bar under normal conditions would be insufficient to force the disk 23 against the tappet 48. Besides, the tappet may be adjusted initially to suit the conditions. The casing 1, being rotatable in its bearings, permits the trolley-pole to be 65 swung 360° (or 180 degrees in either direction) so that the car may be propelled forward or backward.

Having described my invention, what I claim is:

1. In combination with an oscillating trolley-pole, a pinion fixed about the axis of oscillation of the pole, a reciprocating rack-bar meshing with said pinion, a depending forked extension for the rack-bar, a disk secured to the free end of said extension, a second disk playing loosely along the forked extension of the rack-bar, a spring interposed between the disks and tending to force them apart, a stem having a forked terminal secured to the second disk and playing loosely through the disk coupled to the rack-bar, means for coupling said stem to a fixed support and thereby anchoring the second disk against movement, the spring serving to actuate the first disk and rack-bar coupled thereto and oscillate the pole against the trolley-wire and means for releasing the stem and the disk coupled thereto upon the release of the pole from the wire whereby the effective abutment for the spring is destroyed and the pole allowed to drop, substantially as set forth. 95

2. In combination with an oscillating trolley-pole, a pinion fixed about the axis of oscillation of the pole, a reciprocating rack-bar meshing with said pinion, a disk coupled to the rack-bar, a second disk movable to and from the first disk, a spring interposed between the disks, a stem connected to the second disk, a setting lever coupled to the stem, means for locking said lever, and devices interposed between the disk coupled to the rack-bar and said locking means for disengaging said locking means upon an abnormal movement of the rack-bar resulting from the release of the pole from the trolley-wire, substantially as set forth. 100

3. In combination with an oscillating trolley-pole, a pinion fixed about the axis of oscillation of the pole, a reciprocating rack-bar meshing with said pinion, a disk coupled to the rack-bar, a second disk movable relatively thereto, a spring interposed between the disks, a stem connected to the second disk, a setting lever pivoted at one end and coupled to the stem, a spring-controlled ratchet-arm pivoted to the lever, a stationary serrated bearing for said ratchet-arm, a rotatable trigger mounted in proximity to the ratchet-arm, a cam mounted on the axis of the trig- 115

120

125

ger for engaging the ratchet-arm and forcing the latter against its serrated bearing, a spring-controlled latch mounted at one end of the trigger, a reciprocating keeper or bar adapted to engage the latch, a spring-controlled tappet adapted to be struck by the disk coupled to the rack-bar upon release of the pole from the trolley-wire, and intermediate connections between the tappet and the keeper for withdrawing the latter from engagement with the spring latch whereby the trigger is tilted to disengage the cam from the ratchet-arm and the latter withdrawn

from engagement with its bearing, and the setting lever and disk coupled thereto released and the influence of the pole-actuating spring destroyed, the parts operating substantially as, and for the purpose set forth.

In testimony whereof I affix my signature, in presence of 15 two witnesses.

WILLIAM LILE.
